UNITED STATES PATENT OFFICE

146,860

DESIGN FOR A RADIO TRANSMITTER CABINET

Myron E. Kluge, Los Angeles, Calif.

Application March 21, 1946, Serial No. 127,761

Term of patent 3½ years

(Cl. D56—4)

To all whom it may concern:

Be it known that I, Myron E. Kluge, a citizen of the United States, residing at Los Angeles, in the county of Los Angeles and State of California, have invented a new, original, and ornamental Design for a Radio Transmitter Cabinet, of which the following is a specification, reference being had to the accompanying drawings, forming part thereof.

Fig. 1 is a front perspective view showing my cabinet in open position; and

Fig. 2 is a rear perspective view showing my cabinet in open position.

I claim:
The ornamental design for a radio transmitter cabinet, as shown.

MYRON E. KLUGE.
